United States Patent Office

Des. 217,743
Patented June 2, 1970

217,743

BOAT BULKHEAD

Frank W. Butler, 10354 Vanalden,
Northridge, Calif. 91324

Filed Jan. 6, 1969, Ser. No. 15,217

Term of patent 14 years

Int. Cl. D12—99

U.S. Cl. D71—1

Fig. 1

Fig. 2

FIG. 1 is a perspective view of the boat bulkhead showing my new design with the bulkhead panel portion removed;

FIG. 2 is a perspective view of my design with the bulkhead panel portion installed.

The broken lines disclosure is for illustrative purposes only.

I claim:

The ornamental design for a boat bulkhead, substantially as shown and described.
